UNITED STATES PATENT OFFICE.

ROBERT P. REID, OF WATERVLIET, NEW YORK.

CUSHIONED WHEEL.

No. 851,105.

Specification of Letters Patent.

Patented April 23, 1907.

Application filed December 22, 1905. Serial No. 293,002.

To all whom it may concern.

Be it known that I, ROBERT P. REID, a citizen of the United States, residing at Watervliet, county of Albany, and State of New York, have invented certain new and useful Improvements in Cushioned Wheels, of which the following is a specification.

The invention relates to such improvements and consists of the novel construction and combination of parts hereinafter described and subsequently claimed.

Reference may be had to the accompanying drawings, and the reference characters marked thereon, which form a part of this specification.

Similar characters refer to similar parts in the several figures therein.

The single figure of the drawings is a view in side elevation, partly broken away, and partly in section, of a vehicle-wheel provided with my invention.

The principal object of the invention is to provide a simple and efficient cushion for interposition between two members, one of which is capable of movement toward and from the other, whereby the force of a shock or concussion received by one of said members will be largely taken up and dissipated in its transmission through said cushion to the other member.

The invention is applicable to various forms of construction wherein a cushioning effect is desirable.

Referring to the drawing, wherein the invention is shown in its preferred form applied to a vehicle-wheel, 1 is the rim, 2 is the hub, and 3, 3' are the spokes of a vehicle-wheel adapted for use on automobiles or wagons or similar road-vehicles. The hub is made hollow to form a fluid-chamber, 4, surrounding the spindle-bearing, 5, into which fluid-chamber open the inner ends of a plurality of piston-chambers, 6, one for each spoke of the wheel. Located within each piston-chamber is a piston, 7, against the outer side of which bears the inner end of the adjacent spoke, said spoke constituting a piston-rod or spindle and being movable longitudinally through a stuffing-box, 8, on the hub. An extension of the fluid-chamber, 4, is formed within a box, 9, mounted upon, and forming substantially a part of, the hub. The box, 9, is in the form of a cylinder and contains a movable diaphragm or piston, 10, the inner side of which is exposed to the

fluid in the inner annular compartment of the fluid-chamber which is admitted thereto through the passage-way, 11, while the outer side of said diaphragm or piston is exposed to the fluid in the outer end of the box or cylinder, 9, which forms the outer compartment of the fluid-chamber, the fluids in said compartments being prevented by said piston or diaphragm from intermingling with each other.

In the use of my invention, the inner compartment is filled with oil, water, or other comparatively incompressible fluid, 12, and the outer compartment with more-or-less-compressed air or other highly compressible fluid 13 which can be introduced through the valved aperture, 14, in a manner similar to that in which pneumatic tires are inflated. The rim, which may be given any desired degree of flexibility, will, upon encountering an obstacle in the road, yield at the point of contact therewith, causing one or more of the spoke - piston - rods to be forced inwardly, causing the piston or pistons engaged thereby to be driven inwardly along their respective chambers toward the center of the hub. The oil or water, 12, being substantially incompressible, the pressure caused by the inward movement of the pistons is instantly transmitted through the liquid and piston or diaphragm, 10, to the gas in the compartment, 9, which is thereby compressed. As soon as the excess of pressure is removed from the rim, the elasticity of the gas in compartment, 9, restores the various pistons to normal position.

By locating the gas in a compartment separated from the liquid compartment, no opportunity is afforded for escape of the gas past the pistons and through the stuffing-boxes, 8, which need to be made only sufficiently tight to resist leakage of the more dense fluid. Should the gas be admitted to the annular liquid compartment, however, no harm would be done, as in use centrifugal force would maintain the more dense fluid in the outer part of the hub-compartment in contact with the various pistons, and the less dense fluid near the center of the hub, in a manner adapted for carrying out my invention and accomplishing the object thereof.

The box or cylinder, 9, is shown as a separate structure mounted upon the hub-proper, but it is in effect a part of the hub, and the

chamber contained within the box or cylinder, 9, is likewise a part of the hub-fluid chamber.

The several pistons, 10, are preferably made cup-shaped, and have their walls tapering to a comparatively thin edge, which, when subjected to the internal pressure of the fluid-chamber, is expanded sufficiently to form a tight joint with the cylinder-walls, whereby I am able to dispense with a packing for the piston.

I am aware that packing material has been employed upon a piston-head in cup-shaped form, and make no claim broadly to such a construction.

It is characteristic of my invention, so far as the same relates to the construction of a piston-head, adapted for use in a cylinder where said piston-head is exposed to pressure, that the piston-head itself is cup-shaped and has its walls tapering to a comparatively thin and flexible edge on the side exposed to pressure, so that the piston-head itself is caused, by the pressure, to tightly engage the walls of the cylinder without the use of a separate packing device.

What I claim as new and desire to secure by Letters Patent is

1. The combination with a pair of members, one capable of movement toward and from the other; of a plurality of pistons mounted upon one of said members; a plurality of cylinders for the respective pistons

mounted upon the other of said members; and a cushion to which each cylinder is open, comprising confined bodies of gas and liquid respectively, separated from each other by a movable diaphragm.

2. The combination with a wheel-hub provided with a fluid-chamber and a plurality of piston-chambers open to said fluid-chamber; of a wheel-rim; pistons in the respective piston-chambers; spokes interposed between the respective pistons and rim; and a cushioning body comprising two fluids of different degrees of compressibility confined in said hub-chamber.

3. The combination with a wheel-hub provided with a fluid-chamber subdivided by a movable diaphragm, and with a plurality of piston-chambers open to one of the fluid-chamber compartments; of a wheel-rim; pistons in the respective piston-chambers; spokes interposed between the respective pistons and rim; a body of liquid confined within the fluid-chamber-compartment open to said piston-chambers; and a body of gas confined within the other fluid-chamber-compartment.

In testimony whereof, I have hereunto set my hand this 19th day of December, 1905.

ROBERT P. REID.
